UNITED STATES PATENT OFFICE.

DANIEL WRIGHT ATKINS, OF MARION, INDIANA.

HEATER.

1,152,263.

Specification of Letters Patent. Patented Aug. 31, 1915.

Application filed April 13, 1915. Serial No. 21,095.

To all whom it may concern:

Be it known that I, DANIEL W. ATKINS, a citizen of the United States, and a resident of Marion, in the county of Grant and State of Indiana, have invented an Improvement in Heaters, of which the following is a specification.

This invention relates to heating apparatus, and more particularly to a gas heater, the construction of which renders it adaptable for use as a stove or a hot air furnace.

The primary object of the invention is the provision of a gas heater which is simple in construction, effective in producing a maximum of heat, and one which may be manufactured at a minimum cost.

The inventive idea involved is capable of receiving a variety of mechanical expressions, one of which, for the purpose of illustrating the invention, is shown in the accompanying drawing, in which—

Figure 1 is a side elevation of the heater constructed in accordance with the invention. Fig. 2 is a vertical sectional view, and

Fig. 3 is a section on the line 3—3 of Fig. 1.

Referring more particularly to the accompanying drawing, in which like reference characters indicate similar parts, the numeral 5 indicates the base of the heater into which projects the gas pipe 6 leading to the burners 7 for supplying gas thereto for the purpose of generating heat. The base 5 is provided in the top thereof with an enlarged opening 8 through which the heat from the burners 7 passes. Surrounding the opening 8 are a plurality of supporting lugs 9 upon which is mounted a deflector plate or spreader 10 preferably of circular formation and arranged directly over said opening.

Supported by and spaced from the deflector plate 10 by means of a plurality of lugs 11 is the inner casing 12 having the closed lower end 13 and open at its upper end, said casing having on its exterior surface an asbestos covering 14.

An outer casing 15 is mounted upon the top of the base 5 and arranged concentrically with the inner casing 12 so as to form an

annular space 16 between said casings. The top 17 of the outer casing 15 is provided centrally thereof with an opening 18. A depending flue 19 is made integral with or detachably secured to the top 17 in alinement with the opening 18 therein, said flue extending downwardly into the inner casing 12 a distance approximately equal to half its depth. The base 5 is also provided with a plurality of small openings 20 for the admission of air into the heater, whereby proper combustion is secured.

In practice, the heat emanated from the burners 7 rises and strikes the plate 10 and is then deflected to the edge thereof and passes into the annular space 16 between the inner and outer casings.

The outer casing 15 will be effectively heated by reason of the fact that the inner casing is covered with asbestos, thereby preventing any absorption of the heat by the inner casing. The top 17 of the outer casing 15 is also effectively heated, and from thence the heat passes downwardly into the inner casing 12, into the flue 19 and upwardly through the opening 18 into the top of the heater.

I claim:

A heater comprising a base, a burner mounted in said base, an outer casing supported on said base and having an opening in the top thereof, a flue depending from said top in alinement with said opening, a deflector plate carried by said base and spaced therefrom, an inner casing having a closed lower end and an open upper end, said open end extending to within a slight distance of the top of the outer casing, said inner casing being supported by said deflector plate and spaced therefrom and arranged concentrically with said outer casing to provide an annular space therebetween whereby the heat from said burner will have an unobstructed passage upwardly in said space and downwardly into said inner casing, and an asbestos covering for said inner casing.

DANIEL WRIGHT ATKINS.
